A. L. ROBERTS,

ROLLED METAL REINFORCEMENT FOR CONCRETE POLES AND PILES.

APPLICATION FILED NOV. 25, 1919.

1,385,643.

Patented July 26, 1921.

A. L. Roberts INVENTOR
By Seymour & Bright Attorneys

UNITED STATES PATENT OFFICE.

ALVIN L. ROBERTS, OF PHILADELPHIA, PENNSYLVANIA.

ROLLED METAL REINFORCEMENT FOR CONCRETE POLES AND PILES.

1,385,643.

Specification of Letters Patent. Patented July 26, 1921.

Application filed November 25, 1919. Serial No. 340,573.

To all whom it may concern:

Be it known that I, ALVIN L. ROBERTS, a citizen of the United States, and a resident of Philadelphia, in the county of Philadelphia and State of Pennsylvania, have invented certain new and useful Improvements in Rolled Metal Reinforcements for Concrete Poles and Piles; and I do hereby declare the following to be a full, clear, and exact description of the invention, such as will enable others skilled in the art to which it appertains to make and use the same.

This invention relates to a rolled metal reinforcement for concrete poles and piles, and it consists in the details of construction as will be more fully explained and pointed out in the claim.

The accompanying drawing is a view in cross section of my improved reinforcement. The cross section of the reinforcement is H-shaped with side ribs 3 projecting at right angles from the side members 2, in the plane of the web 1 uniting the said side members 2, the whole being rolled in a single piece. This web 1 has parallel faces and the side members 2 are tapered from the web outwardly in opposite directions, being thicker at their juncture with the web than at their free edges. The ribs 3 are made tapering outwardly from their junctures with the side

members, and are preferably of less width than the side members, the web, side members and ribs being of substantially the same thickness at their points of juncture.

This shape is particularly adapted to carry axial loads combined with a horizontal or side load applied in a direction parallel with the web, hence will be particularly useful for reinforcing piles which support a load at the top and also at the sides.

Having fully described my invention what I claim as new and desire to secure by Letters Patent, is:—

A rolled metal shape composed of a web having parallel faces, side members integral with the edges of the web and tapered from the web outwardly, being thicker at their points of juncture with the web than at their free edges and a tapering rib on each side member and in the plane of the web, the web, side members and ribs being of substantially the same thickness at their meeting points.

In testimony whereof, I have signed this specification in the presence of two subscribing witnesses.

ALVIN L. ROBERTS.

Witnesses:

GEORGE MARX,
C. C. HARDING.
